ABSTRACT

This invention relates to a method for improving the oxidative stability of hydrocarbon lubricating oils by contact with a gas containing free oxygen in the presence of a solid basic refractory oxide catalyst, characterized by the presence therein of a minor proportion of alkali metal, under specified conditions of temperature and pressure.

1. Field of the Invention

This invention pertains to production of lubricating oils, of petroleum origin, characterized by improved oxidative stability.

2. Description of the Prior Art

Petroleum lubricating fractions produced by conventional refining techniques including distillation, acid treatment, clay treatment, solvent refining, etc. often possess unsatisfactory oxidation stability in spite of the refining procedures which have been employed. Such unsatisfactory oxidation stability encountered in lube oil fractions frequently gives rise, upon subjection to oxidation, to excessive discoloration, formation of acidic materials and production of heavy viscous sludges and resins which deposit on the surface which it is desired to lubricate.

Due to the lubricant oxidative stability requirements of new larger machinery, engines and the like, feedstocks which were formerly satisfactory for lubricant production are presently unsuitable or at best marginal for such uses. Thus, at a time when overall lubricant demands are increasing and becoming more stringent, the amount of suitable lubricant petroleum feedstock is being diminished due to the oxidative lubricant stability requirements of modern usage.

While some antioxidant additives have been developed as an aid in improving lubricant oxidative stability, such additives have been expensive to employ, particularly in large scale operations.

SUMMARY OF THE INVENTION

In accordance with the present invention, there is provided a method for improving the oxidative stability of a hydrocarbon lubricating oil which comprises contacting said oil with a gas containing free oxygen, such as air, in the presence of a solid basic refractory oxide catalyst characterized by an alkali metal content of at least about 2 percent by weight. Contact is accomplished at a temperature generally in the range of 150° to 550°F., preferably between about 200° and 350°F., at a pressure between atmospheric and 500 psig and at a liquid hourly space velocity of between about 0.1 and about 10 volumes/volume of catalyst/hour.

The feedstocks undergoing treatment in accordance with the method of the invention are those petroleum lubricant stocks resulting from conventional refining such as distillation, followed by solvent extraction, e.g., with furfural, and dewaxing, e.g., with methyl ethyl ketone. The oils are identified according to the source of their crude oil and physical properties. Mid-Continental stocks appear to be particularly suscepti-

20 The feed stock of the type above described is, in accordance with the method of the invention, contacted with a gas containing free oxygen. Such gas is suitably air, but may be oxygen alone or oxygen mixed with diluent gases such as nitrogen, helium, argon or other inert gases. Generally when utilizing air, such gas is fed with the oil feed stock at a rate of at least 2 volumes of air per volume of oil. When utilizing a gas containing 25 free oxygen, other than air, corresponding suitable adjustment in the volume of such gas is contemplated such that the amount of oxygen present is at least about 0.4 volume of oxygen per volume of oil. Contact between the feed stock and the gas containing free oxygen may be effected in any suitable manner including concurrent or counterconcurrent contact in the catalyst bed.

30 The catalyst employed herein is a refractory basic solid having a minimum alkali metal content of approximately 2 weight percent. A wide variety of catalytic materials may be used including alkali metal-containing alumina, silica, crystalline aluminosilicates, both synthetic and natural, ores, clays, such as montmorillonite, and metal ferrites, such as zinc ferrite. 35 Representative of suitable catalysts are the alkali metal crystalline aluminosilicates of the X and Y type. Such materials may include the sodium forms of these synthetic crystalline aluminosilicates in the as synthesized condition or compositions resulting from ion exchange or impregnation with other alkali metals such as potassium, rubidium or cesium. Other feasible catalysts include suitable supports such as alumina or silica having impregnated thereon an alkali metal in the amount of 40 at least 2 weight percent and preferably between about 4 and about 30 weight percent. Representative of such 45 compositions are theta alumina containing about 5 weight percent sodium and silica gel impregnated with sodium and/or rubidium. Other suitable catalysts are 50 clays of the montmorillonite type which are particularly applicable and attractive for use in the present process due to their inexpensive origin. Another catalyst which has been found to be effective is zinc ferrite containing about 5 weight percent of potassium. These 55 catalysts are calcined, generally by heating at a temperature of between about 500° and about 1,000°F. for a period of approximately 3 hours or longer and may thereafter be sulfided by contacting with hydrogen sulfide at a temperature of between about 300° and about 700°F. for a period of time generally in the range of 60 about 2 to about 10 hours. The catalyst is generally in particle form, preferably having a particle size of between about 4 and about 30 mesh. The amount of catalyst employed will generally be in the range of from 65 about 0.01 to about 10 weight percent of the feed stock

60

undergoing treatment. In a fixed bed operation, the oil/catalyst volume ratio will be in the approximate range of 10 to 10,000.

Contact between the feedstock, the oxygen free gas and the catalyst is generally accomplished by continuously passing the feedstock and the oxygen free gas through a bed of the catalyst. Alternatively, the operation may be carried out as a batch process wherein the feedstock is contacted with the catalyst and air or other oxygen containing gas is bubbled into such mixture, after which the treated oil product is removed from the catalyst by any suitable means such as by filtration or distillation to obtain the treated oil product or desired fractions thereof as distillates while leaving undesired reaction products in the residue.

The temperature of treatment is generally between about 150° and about 550°F. Particular preference is accorded a temperature in the approximate range of 200° to 350°F. since it has been established that treatment under the latter temperature conditions produces a product characterized by oxidative stability without detrimentally affecting the color of the resulting product. Operation at a temperature above 350° and up to 550°F. affords a resultant product characterized by improved oxidative stability but it has been observed in some instances that the resulting product has a generally undesired dark color. The pressure at which the described process is carried out is generally atmospheric but may be within the range of from atmospheric up to about 500 psig. Contact between the feed stock and the catalyst generally takes place at a liquid hourly space velocity of between about 0.1 and about 10 volumes of feed stock per volume of catalyst per hour.

DESCRIPTION OF SPECIFIC EMBODIMENTS

The following examples will serve to illustrate the invention without limiting the same:

EXAMPLE 1

A catalyst was prepared by impregnating 10 grams of sodium zeolite X with 20 cc of rubidium acetate solution (containing 0.87 gram of $RbC_2H_3O_2$) to a rubidium level of 5 weight percent. The impregnated material was then calcined to 1,000°F. at a rate of 1°C./minute.

A lube oil stock having the following properties:

Gravity, °API	30.0
Pour Pt., °F.	5
Flash Pt., °F.	425
Sulfur, % wt.	0.27
Nitrogen, % wt.	0.007
Aniline Point, °F.	219.1
Viscosity, S.U.S. at 100°F.	232
Viscosity Index	97
ASTM Color	1½

was passed over the above-described catalyst in an up-flow reactor at 1 LHSV at atmospheric pressure and at a temperature of 400°-550°F. Air was co-fed with the oil at rates of 10 and 5cc of air/cc of oil. The oil products were stripped of any light products and water to an equivalent temperature of 650°F. and tested for oxidative stability.

The test to which the oil product was subjected involves placing a 25 gram sample of the test oil in a 200 mm. × 25 mm. test tube. The test oil has immersed therein (a) 15.6 sq. in. of sand-blasted iron wire, (b) 0.78 sq. in. of polished copper wire, (c) 0.87 sq. in. of polished aluminum wire and (d) 0.167 sq. in. of a pol-

ished lead specimen. The oil sample was heated to a temperature of 325°F. and maintained at such temperature for a period of 40 hours while dry air was passed therethrough at a rate of 5 liters per hour. The change in neutralization number and kinematic viscosity before and after the oxidation are recorded and the weight loss of the leaded specimen is obtained. The improved oxidative stability of the treated oil is shown by the low increase in kinematic viscosity and low increase in neutralization number. The change in kinematic viscosity reflects the rate of production of heavy polymerized hydrocarbon materials due to oxidation, such as sludges, which increase the viscosity. The increase in neutralization number reflects an increase in content of acidic materials in the treated oil.

The results of treating the above oil and testing are shown in the following table:

TABLE I

Bromine No.	0.6	1.0	0.7

EXAMPLE 2

A catalyst of sodium X was employed in treatment of the oil feed described in Example 1 at a temperature of 300° to 400°F., atmospheric pressure and a liquid hourly space velocity of 1.

The resulting oil product was tested as described in the above test with the results shown hereinafter in Table II.

EXAMPLE 3

A catalyst of theta alumina containing 5 weight percent of sodium was used in treatment of the oil of Example 1 at a temperature of 200° and 250°F., at atmospheric pressure and a liquid hourly space velocity of 1.

The resulting oil product was tested as described in the above test with the results shown hereinafter in Table II.

EXAMPLE 4

A catalyst of cesium zeolite Y was obtained by ion exchange of sodium Y with cesium acetate to a cesium level of 5 percent by weight. This catalyst was used in treating the oil of Example 1 at a temperature of 200°F., atmospheric and liquid hourly space velocity of 1. The resulting oil product was tested as described in the above test with the results shown hereinafter in Table II.

EXAMPLE 5

A catalyst of silica gel impregnated with 5 weight percent of rubidium and 5 weight percent of sodium was employed in treating the oil feed described in Example 1 at a temperature of 300° and 200°F. at atmospheric pressure and liquid hourly space velocity of 1.

The resulting oil product was tested as described in the above test with the results shown hereinafter in Table II.

EXAMPLE 6

A catalyst of sodium zeolite X was sulfided by heating in H_2S to 600°F. over a period of 2 hours and held at such temperature for 3 hours. This catalyst was employed in treating the oil feed of Example 1 at a temperature of 200°F., atmospheric pressure and liquid hourly space velocity of 1.

The resulting oil product was tested as described in the above test with the results shown hereinafter in Table II.

EXAMPLE 7

A catalyst of zinc ferrite containing 5 weight percent of potassium was employed in treating the oil feed described in Example 1 at a temperature of 200°F., atmospheric pressure and liquid hourly space velocity of 1.

The resulting oil product was tested as described in the above test with the results shown hereinafter in Table II.

EXAMPLE 8

A sample of sodium Y zeolite was exchanged with rare earth chlorides repeatedly to a sodium level of about 0.5 weight percent. This catalyst was employed in treating the oil feed described in Example 1 at a temperature of 200°F., atmospheric pressure and liquid hourly space velocity of 1.

The resulting oil product was tested as described in the above test with the results shown hereinafter in Table II. The high figures observed for change in kinematic viscosity and neutralization number indicate that the acidic REY product is not an effective catalyst for this application.

Treatment was carried out at atmospheric pressure, a liquid hourly space velocity of 1 and temperatures ranging from 150°F. to 350°F. The feed and the results are shown in Table III below:

TABLE III

Run Number	Feed	13	14	15	16
Treating Condition	—	200	300	250	150
Temperature, °F.	—	—	—	—	—
Product Inspection	1½	1%	2	1½	1%
Color	—	—	—	—	—
Oxidation Test	—	—	—	—	—
(325°F., 40 Hrs)	—	—	—	—	—
ΔKV%	17	10	8	9	10

Lead Loss	3.4	1.2	1.8	—	0.8
Bromine No.	0.9	1.0	1.0	—	1.0

It will be seen from the above data that the oxidative stability of the lube oil feed was considerably improved by reacting it with air over the specified refractory basic solids. The mild treating conditions coupled with the relatively simple procedure of the described treating technique is particularly applicable in upgrading marginal stocks with respect to improvement in oxidative stability.

I claim:

1. A method for improving the oxidative stability of a hydrocarbon lubricating oil which comprises contacting said oil with a gas containing free oxygen and a solid basic refractory oxide catalyst characterized by an alkali metal content of between about 2 and about 30 percent by weight at a temperature in the range of about 150° to about 550°F., at a pressure between at-

mospheric and 500 psig and at a liquid hourly space velocity of between about 0.1 and about 10 volumes/volume of catalyst/hour.

2. The method of claim 1 wherein the temperature is between about 200° and 350°F.

3. The method of claim 1 wherein the gas containing free oxygen is air.

4. The method of claim 3 wherein air is contacted with said oil at a rate of at least 2 volumes of air per volume of oil.

5. The method of claim 1 wherein said catalyst is an alkali metal crystalline aluminosilicate.

6. The method of claim 1 wherein said catalyst is montmorillonite clay.

7. The method of claim 1 wherein said catalyst is silica gel impregnated with alkali metal.

8. The method of claim 1 wherein said catalyst is alumina impregnated with alkali metal.

9. The method of claim 1 wherein said catalyst is zinc 5

ferrite containing alkali metal.

10. The method of claim 1 wherein said catalyst is sodium zeolite X.
